United States Patent Office

Des. 185,606
Patented June 30, 1959

185,606

MOTION-PICTURE CAMERA

Frederick G. Knowles and Jack K. Hockenberry, Rochester, N.Y., assignors to Eastman Kodak Company, Rochester, N.Y., a corporation of New Jersey

Application February 12, 1959, Serial No. 54,592

Term of patent 7 years

(Cl. D61—1)

Fig. 1

Fig. 2

Fig.3

Fig.4

Fig. 1 is a perspective view, taken from the front and showing one side, of a motion-picture camera showing our new design;

Fig. 2 is a top plan view thereof;

Fig. 3 is a perspective view thereof taken from the back and showing the side opposite to that shown in Fig. 1; and

Fig. 4 is a bottom plan view thereof.

The essential features of our design reside in the parts shown in full lines.

We claim:

The ornamental design for a motion-picture camera, as shown and described.
